UNITED STATES PATENT OFFICE.

VINCENT C. DE YBARRONDO, OF LOS ANGELES, CALIFORNIA.

APPARATUS FOR DEVELOPING FILMS.

1,143,892.

Specification of Letters Patent. Patented June 22, 1915.

Application filed April 6, 1914. Serial No. 830,082.

To all whom it may concern:

Be it known that I, VINCENT C. DE YBARRONDO, a citizen of the United States, residing at Los Angeles, in the county of Los Angeles and State of California, have invented 5 a new and useful Apparatus for Developing Films, of which the following is a specification.

The invention relates to the development 10 of moving picture films. These films which consist of thin strips of celluloid after being exposed must be washed and treated with certain chemicals to bring out and fix the image formed by the exposure. The 15 usual method of doing this is to wind the films, which may be 100 ft. or 200 ft. long, upon an open frame, immersing these frames in various solutions. This is objectionable in that the film which comes from the camera 20 wound in a tight roll upon a reel must be unwound upon the frame, and it is further objectionable in that the frames are cumbersome to handle and it is difficult to get an even development thereon. As the pictures 25 themselves are very small and are enormously magnified when thrown upon the screen, small particles of dust which may adhere thereto produce a blurred and indistinct film and it is necessary to carefully 30 protect the film from dust particles during development and washing.

The principal object of the invention is to provide means whereby the films may be directly unrolled from the reel as it comes 35 from the camera and developed in a perfectly flat, straight, condition, all the processes of development, washing, fixing, and drying being performed without additional handling of the film.

40 A further object is to provide means whereby the film will be entirely protected from dust particles during such development and fixing.

A further object is to provide means 45 whereby a large number of films may be quickly and perfectly developed by a single operator in a very economical manner.

In the drawings, which are largely dia- 50 grammatic, and which are for illustrative purposes only, Figure 1 is an elevation partly in section of apparatus adapted to carry on the process. Fig. 2 is a perspective view of a portion of this apparatus, the various parts being broken away to better illustrate the apparatus. Fig. 3 is a partial section on the line x^3-x^3 of Fig. 1. Fig. 4 is a

perspective view of a preferred form of weight. Fig. 5 is an elevation, partly in section, of a portion of an inclined assembling of the invention. Fig. 6 is a section on the line x^6-x^6 of Fig. 5. Fig. 7 is a section on the line x^7-x^7 of Fig. 6. Fig. 8 is a perspective view of a weight showing the method of fastening a film thereto.

In the invention the films are developed 65 in pairs in vertical treating pipes which are long enough to take from 100 ft. to 200 ft. of film. The upper ends of these pipes extend into a dark room, and the films are lowered therein being kept straight by suitable weights which are restrained from turning. While in these pipes all the various processes of washing, developing, fixing, and 70 drying are carried on, the film when withdrawn therefrom being completely developed, 75 fixed, washed and dried.

In the drawings, the treating pipes 1, 2 and 3 extend downwardly through the floor 4 of a dark room. A table 5 is provided upon which may be placed film boxes 6, 7 80 and 8, each of these boxes being large enough to contain two reels of films 9 and 10. One side of the film is coated with a photographic emulsion, and the films are so wound upon the reels 9 and 10 that the emul- 85 sion is on the outer side. The film is passed outwardly through slots 11 formed by rollers 12 in the side of the film boxes 6, 7 and 8 and passes to heads 13 which are secured by means of set screws 14 on the top of the 90 pipes 1, 2 and 3, rollers 15 being provided in the top of this head and the film passing between these rollers. As illustrated in Fig. 1, two films may be extended downwardly in each of the pipes 1, 2 and 3, and the arrangement is such that the emulsion sides are outward, that is to say, the films are back to back in the pipes 1, 2 and 3. A weight 16 is secured to the bottom of each of these pairs of films, this weight consisting of two mem- 100 bers 17 and 18 hinged together at 19. A series of projections 20 in the member 18 register with grooves 21 on the member 17, these projections 20 being suitably placed to pass through the series of small holes which are 105 perforated in each edge of the film. A catch 22 is provided for locking the members 17 and 18 together and a pair of projecting ribs 23 are provided, being on the opposite sides of the weight 16 when the members 17 and 110 18 are swung together. These ribs 23 fit into grooves 24 in the inside of the pipes 1, 2 and

3 and are provided for the purpose of preventing the films twisting. Any other convenient openings 25 are provided through the weights 16 to allow the circulation of 5 liquid therethrough.

Means for keeping the weight from turning, such as irregular shaped pipe, may be used. The reels 9 and 10 are mounted upon shafts 26 which extend through the side of 10 the box and have pulleys 27 thereon. The pulleys 27 are connected by a cross belt 28 and are operated by a handle 29 by which the film may be wound or unwound on the reels 9 and 10, thus raising and lowering 15 them in the pipes 1, 2 and 3.

The method of operation of the invention is as follows: The films being threaded between the rollers 12 in the side of the box 6 are threaded between the rollers 15 in the 20 cap 13, and the weight 16 is secured by clamping the members 17 and 18 together by means of the catch 22. The cap 13 is then placed upon the pipe 1 and secured by the set screw 14. The handle 29 is then 25 turned lowering the films in the pipe 1, the weight 16 tending to keep them straight and flat. The films are now allowed to remain in the pipe during the entire developing, 30 fixing, washing, and drying processes which will now be described.

A water pipe 30 connects through a valve 31 with a source of clean water supply, this water pipe 30 being in open communication with a water head 32 which extends across 35 the dark room and which communicates through valves 33 with pipes 34 which are in open communication through the crosses 35 of the pipes 1, 2 and 3. A developer tank 36 communicates through a valve 37 with a 40 developer head 38 which communicates through valves 39 with the pipes 34 which are in open communication, as previously explained, with the pipes 1, 2 and 3. The fixing solution is carried in a tank 40 which communicates through a valve 41 with a fixing head 42 which communicates through valves 43 with the pipe 34 which communicates with the pipes 1, 2 and 3. A hot air head 44 is provided communicating 45 through valves 45 with the cross 35, this hot air head 44 being supplied through a pipe 46 from a blower 47 driven from a motor shown in dotted lines, the hot air being derived through a pipe 48 from the 50 heater 49 which consists of a heating coil 50 connected to a burner 51 supplied with gas or other fuel through the pipe 52. A filtering device 53 removes all dust particles from the air entering the heater 49. The lower 55 ends of the pipes 1, 2 and 3 are secured in crosses 54. The lower end of these crosses are connected with a sewer pipe 55 through pipes 56 and through quick acting valves 57 which are operated through rods 58 by 60 means of handles 59 which pass through the

dark room floor 4. The crosses 54 also connect through a series of valves 60, similarly operated through rods 62, by a hand wheel 61 above the floor 4, with a pipe 63 which communicates through a check valve 64 with a 70 developer pump 65, this pump being driven by an electric motor 66 and being in open communication with a pipe 67 which extends upwardly into the top of the developer tank 36. In a similar manner the crosses 54 communicate through a series of valves 68 which are operated from above the floor 4 by handles 69 through rods 70, with a fixing pump 71 which is driven by an electric motor 72 and which communicates with the 80 fixing tank 40.

The method of treating the film will be described in connection with the treating pipe 1, the method of handling in pipes 2 and 3 being exactly similar. When the film 85 is first lowered into the pipe 1, it is desirable to first wash it in clean water to remove any dust which may adhere thereto. For this purpose the valve 57 is opened by means of the handle 59 and a supply of clean water 90 is admitted to the pipe 1 through the valve 33 from the water head 32, the valves 39, 43 and 45 being closed while this is taking place. This water passes downwardly over the films in the pipe 1, thoroughly washing 95 same, and passes off through the sewer pipe 55, the valves 60 and 68 being closed during this operation. The developer pump 65 is then started and the valve 60 is slightly opened by means of the handle 61. The 100 valve 33 is closed and the valve 37 is opened, thus admitting developer to the developer head 38. The valve 39 is then fully opened allowing the pipe 1 to quickly fill with developer. This developer is slowly removed 105 from the bottom of the pipe 1 and returned to the tank 36 through the pipe 67, this slow circulation of the developer serving to maintain it at an equal strength throughout the pipe 1 and thereby evenly developing the 110 films. After a sufficient length of time has elapsed to thoroughly develop the films, the valve 39 is closed and the valve 60 is fully opened thereby allowing the pump 65 to 115 fully drain the pipe 1 of developer which is returned to the tank. The valve 60 is then closed, the valve 57 is opened, and a supply of water is admitted through the valve 33 for the purpose of thoroughly washing out 120 any developer which may adhere to the films or to the interior of the pipe 1, and its connecting pipes. This water is drained by the sewer pipe 55 as before. The valve 57 is then closed and the fixing pump 71 is started, the valve 68 being slightly opened 125 by means of the handle 69. The fixing solution is then admitted to the fixing head 42 by opening the valve 41 and this solution is admitted to the pipe 1 through the valve 43. This fixing solution is allowed to fill 130

the pipe 1 and is slowly circulated through that pipe by means of the pump 71, being returned to the tank 40 through the pipe 73. This fixing process is allowed to continue 5 for a considerable period after which the valve 43 is closed and the valve 68 is fully opened allowing the pump 71 to return the fixing solution to the tank 40 through the pipe 73. The valve 68 is then closed and 10 the valves 57 and 33 are opened thereby thoroughly washing the film, the waste water being carried away by the sewer pipe 55. After the film is fully washed the valve 33 is closed, the valve 57 being still left fully 15 open. The blower 47 is then started, the burner 51 being lighted under the coil 50 in the heater 49. The valve 45 is then opened and the blower 47 forces filtered air from the filter 53 through the coils 50, where it is 20 heated, and through the pipe 46 into the interior of the pipe 1. This heated filtered air flows downwardly through the pipe 1 and away through the sewer pipe 55, thoroughly drying the films in the pipe 1 during 25 this passage therethrough. When the films are thoroughly dried the valve 45 is closed and the films are wound on the reels 9 and 10 by means of the handle 29, the cap 13 being removed and the weights 16 being 30 taken from the end of the films.

It is evident that the arrangement of pipe is such that the above operations may be carried forward simultaneously in any or all of the pipes 1, 2 and 3, the operator washing 35 a film in the pipe 1 and carrying out any of the other processes in any of the other pipes at the same time, if he desires. It is also evident that a single film may be developed, if desired, in place of the two films 40 shown, or that additional or different solutions than those described may be used. It is also evident that inasmuch as the film is held straight and flat, supported only at its 45 extreme end, and as further all the operations are carried forward in a closed pipe, without handling the liability of damaging the film is very small and the films may be developed quickly, safely and perfectly by the above described apparatus.

50 In some locations it is more or less difficult to find a location in which the pipes may be held strictly vertical, and in such locations it is practical to incline the pipe slightly by using the form of construction shown in 55 Figs. 5, 6, 7, and 8. In these figures, 75 is one of a series of pipes corresponding to the pipes 1, 2, and 3, in the previous figures, the upper end of this pipe extending into a dark room 76 and the lower end connect-

ing with a sewer pipe 77, the pipe being supported intermediate of its length upon supports 78. The pipe 75 is provided with valves and pipe connections exactly similar to those already described in the case of the previous figures and the method of treating 60 the film in the pipe is exactly the same as that already explained. It is necessary, however, to provide means for supporting the film to prevent it rubbing against the side of the pipe, and for this purpose a longitudinal molding 79 is secured by means of molts 80 in the center of the pipe, this molding having grooves 81 and 82 in opposite sides thereof of sufficient width to exactly take a film 83. A lead weight 84, which is provided 75 with a thumb nut 85, is secured to the lower end of the film and tends to pull it downwardly in the grooves 81 and 82. The film is so placed in these grooves that the emulsion side is outward, and the method of 80 treating is that which has already been described.

I claim as my invention:

1. An apparatus for developing films comprising a pipe having an elevated end, means 85 for passing a film into said elevated end, a weight fastened to the end of said film sufficiently heavy to draw the film into said pipe, and means for preventing the weight from turning as it travels through said pipe. 90

2. An apparatus for developing films comprising a pipe, means for passing various fluids through said pipe, a weight adapted to be fastened to the end of the film, and means for preventing the weight from turning 95 as it passes through the pipe.

3. An apparatus for treating films comprising a pipe, means for passing treating fluids through said pipe, a weight adapted 100 to be secured to the end of the film, and projections on said weight sliding in grooves in said pipe.

4. An apparatus for treating films comprising a cylindrical pipe, means for passing a film into the top of said pipe, a weight secured to the bottom of said film, means on 105 said weight coöperating with said pipe to prevent the weight from twisting the film as it passes downwardly through said pipe, and means for passing treating fluids over said film as it passes into said pipe. 110

In testimony whereof, I have hereunto set my hand at Los Angeles, California, this 30th day of March, 1914.

VINCENT C. DE YBARRONDO.

In presence of—

FRED A. MANSFIELD,
FORD W. HARRIS.
